COMBINATION BILL AND COIN HOLDER

Henry King Rosenbaum, Jackson Heights, N. Y., assignor to Waybell Mfg. Company, Inc., New York, N. Y., a corporation of New York

Application July 10, 1952, Serial No. 20,534

Term of patent 14 years

(Cl. D87—3)

To all whom it may concern:

Be it known that I, Henry King Rosenbaum, a citizen of the United States of America, residing at 35-24 72nd Street, Jackson Heights, in the county of Queens and State of New York, have invented a new, original, and ornamental Design for a Combination Bill and Coin Holder, of which the following is a specification, reference being had to the accompanying drawing, forming part thereof.

In the drawing

Fig. 1 is a perspective view of the interior of a combination bill and coin holder showing my new design;

Fig. 2 is a perspective view of the outer face of the article likewise in open flat position;

Fig. 3 is an end elevational view taken at the coin holder portion of the article; and

Fig. 4 is a view similar to Fig. 3 taken at the opposite end of the article.

I claim:

The ornamental design for a combination bill and coin holder, substantially as shown.

HENRY KING ROSENBAUM.
